UNITED STATES PATENT OFFICE.

ALEXANDER S. MACKENZIE, OF HOUSTON, TEXAS, ASSIGNOR TO CLAYTON GIN COMPANY, OF HOUSTON, TEXAS, A CORPORATION OF TEXAS.

TEMPORARY BALE FASTENING.

Application filed March 2, 1925. Serial No. 12,643.

To all whom it may concern:

Be it known that I, ALEXANDER S. MACKENZIE, a citizen of the United States, residing at Houston, in the county of Harris and State of Texas, have invented new and useful Improvements in Temporary Bale Fastenings, of which the following is a specification.

This invention relates to temporary fastening means for securing wrappers about commodities which it is desirable to enclose within an envelope or wrapper, and as here disclosed, is shown in connection with the wrapping and temporarily securing of the burlap or fabric wrappers with which it is usual to envelop or wrap round bales of cotton.

This development is an improvement on those devices shown in the patents to George R. Brown, Nos. 1,193,506, August 8, 1916, and 1,247,630, November 27, 1917.

The invention is of the same general type as the devices shown in these patents, and has the same object in view, namely, to provide a convenient temporary fastening means which may be attached to the wrapper, and, as that wrapper is fed through the press during the step of covering the bale, such fastening means will temporarily hold the cover in snug condition about the bale ready for the permanent sewing or securing of the wrapper.

In order that the invention may be clear to those skilled in the art, I have shown, in the accompanying drawings, one embodiment of my invention, it being understood that this disclosure is illustrative, and in no sense restrictive, as variations from the form here shown, which are within the skill of the mechanic, or involve the substitution of obviously equivalent expedients, may be made, and still be within the range of my invention.

In the drawings:—

Fig. 1 is a view, somewhat diagrammatic, of a round bale press and a portion of a cover wrapped around the completed bale.

Fig. 2 is a view in plan of the under or pronged side of the temporary fastening device.

Fig. 3 is a view in side elevation of the fastening device.

Fig. 4 is a view in end elevation, looking from the right of Fig. 2.

Figs. 5 and 6 are diagrammatic views to

show the manner of attaching the fastening device to the cover preliminary to entering the press.

Fig. 7 is a diagrammatic view showing the action of the fastener as it enters beneath the press roller.

Referring to the drawings by numbers, like numbers indicating like parts in the several views, 10 indicates generally a press of any desired type designed for forming 65 a round bale from a suitable bat of cotton. The formed bale is shown at 11 with the cover 12 partially wrapped about the bale, this cover 12 being generally of burlap or other suitable fabric, and passing to 70 the press in a continuous sheet from the wrapper roll 13, disposed in proper relation to the press.

The bale 11 will, of course, be formed in the usual manner by feeding the bat down 75 the feed chute 14 to the rollers 15 of the press, and when the bale has been formed, the cover 12 will then be fed into the press, and, by continued operation of the press, wrapped around the bale until it is brought to the 80 overlapped position indicated at 16 in Fig. 7. The continuous length of fabric coming from the roll 13 will, of course, be severed at an appropriate point between the press and the roll 13, after the bale 11 has been 85 completely wrapped and the ends of the cover have been brought to the overlapped position disclosed in Fig. 7.

In this position, the bale is completed, the cover has been applied, and the covered bale 90 is ready to be removed from the press.

It is necessary, however, and broadly is old in the art, as shown by the patents to Brown noted above, to temporarily secure the cover 12 at its lapped ends, in order 95 that when the bale is removed, the expansion of the highly resilient cotton will not displace the cover and distort the compressed and symmetrical base.

In my present improvement, this is 100 accomplished by the use of the temporary fastening device shown in detail in Figs. 2, 3 and 4. The device, as there shown, comprises the fastener made up of the body portion 17, which, as will be seen in Fig. 3, 105 is curved, the curvature of this body portion approximating the curvature of a press roll 15, as will be clear from Fig. 7. With the body portion 17 curved as shown, when the fastener passes beneath the roller and is sub- 110

jected to the high compression of such roller, it will, by reason of its conforming to the curve of the roll, pass beneath it without any danger of distortion or upsetting under pressure, and will ensure proper engagement of the fastener with the cover and bale. At one end of this curved body portion 17 are provided the overhanging hooks 18, these hooks being relatively short and having a considerable overhang, as shown in Fig. 3. The hooks 18 are designed for attaching the fastener to the web of fabric, as it descends from the roll 13 toward the press, as shown in Figs. 1, 5 and 6.

15 At the other end of the plate 17 are the relatively long hooks 19 which have a slight overhang and are intended to penetrate the cover and bale, as shown in Fig. 7, when the fastener passes beneath the roll 15. If desired, the hooks 19 may be barbed as at 20, see Fig. 4, so that they will not accidentally withdraw or spring out of the bale and cover after once having been engaged therewith.

25 The fastener 17 may be conveniently secured to the fabric as it passes from the roll to the press, as shown in Figs. 5 and 6. The overhanging hooks 18 will be first engaged with the fabric, and after the fastener is brought to the position shown in Fig. 5, the 30 long relatively straight hooks 19 may be thrust through the fabric to the position shown in Fig. 6, although it will be obvious that the fastener might be carried into the press in the position shown in Fig. 5, and 35 pressure of the roll 15 will at once thrust the long hooks 19 through the lapped covers and into the bale.

When the fastener is in place on the cover and the covering fabric passes through the 40 press, the hooks 19 will be forced through the lapped ends of the cover and into the bale. The overhanging hooks 18 are securely caught in the fabric, as described, so that a 45 sure temporary fastening of the cover about the bale results.

When the bale is removed from the press, its natural expansion, when relieved of pressure, will tighten the cover, and the hooks 18 and 19, due to their overhang, will resist 50 any tendency of the device to slip from place and release the cover. Furthermore, the curved body portion 17, being curved downwardly on the side from which the hooks project, gives great rigidity and 55 resistance against straightening under pull of the hooks, even though the device be made of comparatively light metal.

The body portion 17 will, by reason of its curved form, pass the rollers 15 without 60 danger of bending and distorting the fastener under the heavy pressure of the rollers, which distortion would tend to destroy the efficacy of the device.

Such changes from the form shown here- 65 in as are equivalent expedients and do not

depart in principle from my invention, may be made and still be within its range.

For example, I have shown a fastener having a plurality of hooks at each end. It is conceivable that a fastener might be provided with a single hook at each end. Again, the fastener is shown as made of a solid plate of metal, but it would be entirely within the range of my invention to make it in skeleton form, or fabricated of wire 75 of suitable gauge. Such changes would, of course, merely call for mechanical skill, and be patent variations of my invention.

I claim:

1. A fastener of the class described comprising a body portion; short, overhanging hooks at one end of said body portion; and a relatively long, straight hook at the opposite end of said body portion provided with a barb. 80

2. A fastener of the class described comprising a body portion; a plurality of short, overhanging hooks at one end of said body portion, and a plurality of relatively long, straight hooks at the opposite end of said body portion provided with engaging barbs 90 in their edges.

3. A fastener of the class described comprising a body portion; short hooks at one end of said body portion turned inwardly 95 thereon with a marked overhang, and relatively long, slightly overhanging hooks turned inwardly at the opposite end of said body portion.

4. A fastener of the class described comprising a body portion; short hooks at one end of said body portion turned inwardly thereon with a marked overhang, and relatively long, slightly overhanging hooks turned inwardly at the opposite end of said 105 body portion, said last named hooks having engaging barbs thereon.

5. A fastener of the class described having a body portion curved longitudinally, short overhanging hooks at one end of said body portion turned inwardly thereon with a marked overhang, and relatively long straight hooks at the other end of said body portion. 110

6. A fastener of the class described having a body portion curved longitudinally, short overhanging fabric engaging hooks at one end of said body portion, and relatively long straight cover and bale engaging hooks at the opposite end of said body portion adapted to penetrate a lapped cover and bale when fed into a baling press. 115

7. A fastener of the class described having a body portion; short, sharply overhanging hooks at one end of said body portion, and relatively long, slightly overhanging hooks at the other end of said body portion. 125

8. A fastener of the class described having a body portion curved longitudinally; short, sharply overhanging hooks at one end 130

of said body portion on the convex side thereof; and relatively long, slightly overhanging hooks at the opposite end and on the convex side of said body portion.

- 5 9. A fastener of the class described having a body portion curved longitudinally; short, sharply overhanging hooks at one end of said body portion on the convex side thereof, and relatively long, slightly overhanging hooks at the opposite end of said
- 10 body portion on the convex side thereof,

said last mentioned hooks having engaging barbs in their edges.

10. A fastener of the class described having a body portion and overhanging hook members at each end of said body portion, said hook members being provided with barbs extending inwardly from the outer edges of the hook members. 15

In testimony whereof I have hereunto set my hand. 20

ALEXANDER S. MACKENZIE.
